LOW TEMPERATURE CARBONIZATION OF
COAL

Stuart Parmelee Miller, Englewood, N. J., assignor
to The Barrett Company, New York, N. Y., a cor-
poration of New Jersey

Application July 19, 1930, Serial No. 469,039

3 Claims. (Cl. 202—30)

This invention relates to low temperature car-
bonization of coal by direct contact between the
coal and hot foul coal distillation gases. The heat
of the coal distillation gases is used to carbonize
the coal. The invention includes both the process
and apparatus for carrying it out.

According to this invention hot coal distilla-
tion gases which may be collected from a number
of coke ovens or gas retorts are brought into direct
10 contact with coal while the gases are still at a
temperature sufficiently high to carbonize the
coal and produce coke therefrom. The word
“coke” as used in this application includes semi-
coke or high volatile coke, the char produced
15 from non-coking coals. The coal distillation
gases used to effect the low temperature car-
bonization and produce coke are high temperature
distillation gases and “hot coal distillation” gases
20 as used herein refers to hot foul high tempera-
ture distillation gases such as coke oven gases
or gas retort gases and does not include low
temperature gases which are not sufficiently hot
to effect low temperature distillation.

Coke ovens are operated at a temperature up
25 to about 1000-1200° C., and are especially suit-
able for furnishing hot gases for carrying out
this invention. Low temperature carbonization
of coal is carried on at lower temperatures, for
30 example at temperatures of 450 to 700° C., and
a high yield of distillate of characteristic prop-
erties is obtained as well as a coke residue which
may be a high volatile coke or semi-coke or char.
The temperature at which the low temperature
35 carbonization is carried out is sufficiently lower
than the temperature at which by-product coke
ovens are operated to make advantageous the use
of hot foul by-product coke oven gases as a
source of heat for carrying on low temperature
40 carbonization.

40 The temperature, composition and rate of evo-
lution of the gases coming from a single coke oven
or gas retort varies during the cooking of a
charge of coal in the oven. On collecting the
45 gases from a number of ovens charged in rota-
tion in an insulated header or collecting main,
a gas stream of substantially uniform tempera-
ture, composition and amount is obtained. By
properly insulating the header or main the gases
50 may be conveyed to the low temperature car-
bonizing apparatus at a temperature only slightly
lower than the mean temperature at which the
gases leave the ovens. By collecting in the hot
gas header only gases from a selected portion of
55 the coking cycle, the temperature of the gases
employed in the carbonizing operation can be reg-

ulated. By selecting the gases from only the
hottest portion of the coking cycle, for example,
the temperature of the gases employed will be
above the mean temperature of the total com-
bined gases from a number of ovens. The ovens 60
connected with the hot header or other collect-
ing means for conveying the gases to the low
temperature retort are preferably also connected
with a collector main of the usual type and by
manipulation of valve means connecting the ovens 65
with the header and with the usual collector
main, the gases from only a selected portion of
the coking cycle may be sent thru the header
to the carbonizing apparatus and when the car-
bonizing apparatus is not in use the gases from 70
the entire coking cycle may be collected in the
usual collector main.

Hot foul coal distillation gases comprise con-
densable constituents including light oils, me-
dium and heavy oils and also heavy and greasy 75
constituents, and in addition, entrained particles
of coke, dust and pitch. When coal is brought
into direct contact with the hot gases in order to
effect its carbonization, the gases are cooled, con-
densable constituents are condensed, and such 80
condensed materials together with more or less of
the entrained impurities may separate from the
gases on to the coal. The degree to which the
gases are cooled and to which condensable con-
stituents are separated, depends upon the initial 85
temperature of the hot gases, the amount of con-
tained condensables and the amount and temper-
ature of the coal brought in contact with unit
quantity of gas. The water content of the coal
also affects the extent of the cooling of the gas 90
and of the condensation of oils, etc. The per-
manent gases, such as hydrogen, methane, etc.,
contained in the hot coal distillation gases to-
gether with oils not condensed and suspended
material not removed by contact with the coal will 95
pass thru the low temperature carbonizing retort
and blend with the gases and vapors generated in
this retort, and on subsequent cooling a combined
tar will be obtained which comprises both pri-
mary tar and constituents ordinarily present 100
in coke oven tar. The resulting gases may be
further treated for the recovery of ammonia, light
oils, etc. The resulting permanent gases may
be sold as fuel, either alone or blended with coke
105 oven gas, producer gas or water gas, etc. The
gases may be used, at least in part, for heating
the coke ovens or gas retorts in which the hot coal
distillation gases are generated, although, due
to their high calorific value, they may be sold as
110 fuel gas.

By cleaning the distillation gases as they leave the low temperature carbonizing apparatus and carrying the cleaning operation out at a temperature not greatly below the temperature at which the gases and vapors leave the low temperature carbonizing apparatus, and then subsequently cooling the clean gases, clean oil products may be produced directly. The cleaning operation may be carried on in an electrical precipitator or in a hot pitch scrubber of the type which contains a small body of pitch and in which a rapidly rotating roll or other element of generally cylindrical contour dipping into the body of pitch is rotated at high speed to spray the gases passing thru the scrubber. In a scrubber of this type a fine intense spray of the pitch sufficient to substantially detar the gases may be maintained.

The coal to be carbonized at low temperature may be of any suitable size depending upon the method to be employed. Crushed or pulverized coal may be used to advantage since with a coal of this size a large surface of the coal is exposed to the heating action of the gases and the coal may therefore be rapidly heated throughout and the low temperature carbonization carried out relatively rapidly and a uniform product obtained. While lignite, brown coal and Illinois non-coking coals are particularly well adapted to carbonization at low temperature by coke oven gases, nevertheless bituminous coals in general may readily be carbonized.

Various types of apparatus have been employed for low temperature carbonization of coal. Certain types of apparatus are particularly adapted for handling certain coals, i. e. coals of high or low volatile content, etc.

The coal may be showered down a tower counter-current to a stream of hot coal distillation gases which are passed up the tower. As the coal passes down thru the tower it comes into contact with gases of gradually increasing temperature and its temperature is raised, and with a tower of sufficient height the temperature at which the semi-coke or coke leaves the bottom of the tower may be only slightly less than the temperature of the entering gases.

The coal may be added to the top of a tower up through which hot coal distillation gases are passing and the coal may accumulate in the tower and build up a charge of coal within the tower to be heated. The rate at which the gases traverse the tower and the rate at which coal is fed to the tower are so regulated that the coal undergoes the desired heat-treatment within the tower. The coke produced may be discharged from the bottom of the tower at a rate commensurate with the rate at which the coal is added to the top of the tower.

Instead of employing a retort of the tower type a retort may be used thru which the hot gases pass and in which the coal is tumbled or agitated. Chains or other tumbling means, etc., may be provided to prevent the coal from adhering excessively to the walls of the retort.

Any suitable type of horizontal or inclined retort may be employed and the gases may pass thru the retort in a direction countercurrent or concurrent with the flow of the coal or coke thru the retort. Concurrent flow of the solid material and hot gases has the advantage that it lessens the condensation of tar or oils from the hot gases by contact with colder fuel in the retort. With concurrent flow of fuel and gases the entering fuel is brought into direct contact with the hot

test gases and the semi-coke resulting from the low temperature carbonization is discharged from the retort at substantially the temperature at which the distillation gases leave the retort, which is sufficiently high to carry with it desired vapors including vapors from the low temperature carbonization and also vapors present in the hot coal distillation gases as they enter the carbonization retort.

Countercurrent flow of solid material and gases, on the other hand, has the advantage that the coal reaches a higher maximum temperature in the retort since it leaves the retort in contact with the hottest gases. With countercurrent flow the coal on entering the retort comes in contact with gases that have already been partially cooled by contact with coal, and as the coal passes thru the retort it is brought into contact with gases of progressively higher temperatures. The coal after being preheated in this manner then comes into contact with the gases entering the retort, which are at their maximum temperature.

The coal may be conveyed thru a horizontal or inclined retort by worms or chains, or rakes or bars, or other suitable means.

In a vertical retort the coal may be carried up thru the retort by means of a helix attached to a rotating shaft or cylinder. The gases may pass down thru such a retort in which case the gases and coal flow in a countercurrent direction. Where concurrent flow of the gases and fuel is desired the gases may be passed up thru the retort. The carbonization may be conducted in equipment such as the Plassmann retort in which the coal is held in relatively thin layers between stationary metal plates. Hot gases are forced thru the coal to accomplish carbonization.

It may be advantageous to preheat the coal before it enters the low temperature carbonization retort. This preheating operation may be effected by direct contact of the coal with a regulated supply of hot coke oven gases. In such a preheating operation the moisture adhering to the coal is volatilized and in general the temperature of the preheating chamber or retort may be raised to approximately 200 or 250° C., without any substantial distillation of the coal, although the temperature to which the coal may be heated depends on the kind of coal employed. The preheated coal may be then fed to a secondary retort of any of the types named and subjected to low temperature carbonization therein.

When the coal brought into direct contact with the hot coal distillation gases is pulverized coal the gases leaving the retort may be passed thru a centrifugal separator or other gas cleaning means to remove entrained particles of the coal from the gases before they enter the condensing system.

The heat which is made available, according to the present invention, for useful purposes, will be appreciated from the fact that in an ordinary coke oven plant containing sixty ovens, each charged with fifteen tons of coal, and carrying out the coking operation over a period of eighteen hours, there will be produced from each oven approximately 650,000 cubic feet of gas at about 600° C. during the coking period, or there will be continuously produced from the sixty ovens around 39,000,000 cubic feet of gas at a temperature around 600° C. or higher in eighteen hours. Such a volume of gases at such temperature will contain upward of around 815,000 B. t. u. per minute available above 150° C., or around 570,000 B. t. u. per minute available above 300° C.

With countercurrent flow of hot gas and coal in a continuous low-temperature carbonization retort, practically all the heat made available by the temperature drop, less radiation losses, may be utilized in effecting the carbonization of the retort charge. In cases where the carbonization requires a gross heat in-put of 800 B. t. u., per pound of coal, and where the heat loss by radiation is 20%, 34,000 pounds of coal may be carbonized per hour, the gases issuing from the retort at about 300° C.

The temperature at which the hot gases leave the retort will determine the type of tar recovered from them. Gases leaving at say, 300° C., will, on cooling, deposit a tar containing a considerable range of high boiling oils, resins, greases, etc., while gases leaving at a lower temperature, say, 150° C., will contain much less of such constituents.

Tar and pitch constituents produced both in the coke ovens or other high temperature coal distillation units, and in the low temperature carbonization retort are carried by the gas and gradually deposited as the gas cools. Such constituents as these which are not carried out of the retort by the gases are eventually carbonized in admixture with the retort coal charge.

The invention will be further described in the accompanying drawings in connection with various types of equipment employed in combination with a coke oven battery, but it is intended and is to be understood that it is not limited thereto:

Fig. 1 is a plan view of a low temperature carbonizing retort in combination with a coke oven battery;

Fig. 2 is an elevation of the apparatus shown in Fig. 1;

Fig. 3 is a section on line 3—3 of Fig. 2.

Fig. 4 is a part section part vertical elevation of the uptake pipe and header assembly of Fig. 2. The sectional part is taken on line 4—4 of Fig. 2.

Figs. 5 and 6 are an elevation and section of a modified type of apparatus; and

Fig. 7 shows low temperature carbonizing apparatus for a two-stage process in which the coal is preheated in the first stage and carbonized in the second stage.

In the drawings, 5 is a coke oven battery. The collector main 6 connects with the individual ovens of the battery thru the uptake pipes 7. A cross-over main 8 connects the collector main with condensers, etc. This apparatus may be of the usual type and is shown more or less schematically in the drawings.

At the opposite side of the coke oven block is a hot gas header 10. It is heavily insulated as shown at 11. The hot gas header is built in sections with cleanout doors 12 for scraping and cleaning out the hot gas header when required. The hot gas header leads into the rotating retort 13. The retort is slowly rotated thru suitable driving gears by the motor 14. The gases enter the retort from the hot gas header thru the coke discharging chamber 15. This chamber is sealed to the retort 13 by means of the stuffing box 16. Low temperature coke produced in the retort 13 is discharged thru this chamber 15 thru the leg 17 and quenching tank 17' into the bin 18. The rotating gates 19 retain a portion of the finished coke in the leg 17 where it is cooled. The bottom of leg 17 is sealed in the quenching water in tank 17'.

A pipe 20 enters the head 21 on the upper end 75 of the retort 13 thru a suitable stuffing box. The

coal is charged to the retort thru this pipe from the hopper 22 and the gases and vapors escape thru this pipe to the condensers 23. Beyond the condensers is an exhauster 24 for drawing the gases, etc. thru the system.

The condensers may be of any desired type. Direct condensers or indirect condensers may be employed. Fractionating condensers may be employed to collect desired distillate fractions. In the drawings ordinary direct condensers are employed. The condensate and water or ammonia liquor used for cooling the gases are drawn off into the decanter 25. From the decanter the ammonia liquor and tar are separately collected in the tanks 26 and 27.

In passing thru the retort 13 the hot coke oven gases from the header 10 produced by the distillation of coal are brought into direct contact with coal from the hopper 22. The hot gases and coal pass thru the retort in a countercurrent direction.

The hot incoming gases are brought into direct contact with the coke being discharged thru 15. The partially cooled gases leaving the retort thru the main 20 come into contact with the coal entering the retort. The gases leaving the retort are cooled to a temperature somewhat above that of the incoming coal. Such countercurrent flow of the coal and gases is economical from a heat standpoint. Some tar will be condensed from the coke oven gases and separate on the coal in the 100 retort 13, especially in the cold end of the retort at which the coal enters. This tar may be distilled to pitch and then to coke. This coke will adhere to the coke produced by the low temperature carbonization of the coal and will be discharged with this coke thru the discharge leg 17 into the bin 18. The tar collected in the tank 27 is a combined tar comprising constituents condensed from the coke oven gases and constituents distilled from the tar during the low temperature 110 carbonizing process. Concurrent flow of the coal and gases may be employed where preferred.

In Figs. 5 and 6 apparatus is shown in which the coal and hot gases pass thru the low temperature carbonizing retort in a concurrent direction. 120 Hot coke oven gases from selected ovens of the battery 5a in which coal is distilled are collected in the hot gas header 10a. The hot gases from this header enter the retort 40 in which they are brought into direct contact with coal admitted to the retort from the hopper 41. In the retort is an oscillating arm 42 driven by the oscillating apparatus 44 which may be of any suitable type well known in the art. On the oscillating member 42 are agitating arms 45. These are oscillated within the retort keeping the coal in motion and agitating and stirring the coal and semi-coke or coke within the retort to prevent its adhering to the walls of the retort and becoming coked on these walls. The agitating arms 45 are provided 130 with suitable shoes 46 for scraping the bottom of the retort. Scrapers 47 are arranged in the upper portion of the retort to remove any material which may adhere to the arms and shoes 45 and 46.

The coke is discharged from the retort thru the discharge leg 50. It is quenched and then collected in the bin 51. The hot gases and vapors pass from the retort into the condenser 52. An exhauster is shown at 53.

The hot coke oven gases, as they enter the retort 40 from the hot gas header 10a come in contact with fresh coal discharged from the hopper 41. The coal is agitated in an atmosphere of the hot gases in the retort 40 and is heated, and 150

on further heating becomes plastic and finally forms semi-coke or coke. The retort 40 is provided with suitable agitating means to prevent any undue adhesion of plastic material to the walls of the retort. On further heating the material being coked passes from the plastic stage to semi-coke or coke. The coke produced in a still of this type in which the material is subjected to constant agitation during the coking operation is more or less lumpy or granular, the pieces not being small. In general the gases will leave the retort 40 at a higher temperature than when countercurrent flow is employed, and the coke made will, therefore, contain less of the products derived from condensate from the coke oven gases. Coal may also be carbonized by countercurrent flow of the coal and the hot gases in this type of retort.

The third modification of apparatus shown in the drawings provides means for a two-stage carbonizing process. Two towers are arranged one above the other. In the upper tower 60, which may be termed the primary distillation chamber, the coal is preheated and dried. In the lower tower 61 the preheated and partially distilled coal is carbonized and coke is produced. Hot coke oven gases from selected ovens of the battery 5b wherein coal is being distilled are collected in the hot gas header 10b. A small portion of these gases is supplied thru the line 62 into the bottom of the primary distillation chamber 60. Hot coke oven gases are admitted to the bottom of this tower in a quantity sufficient to raise the temperature of the coal to, for example, 300 or 325° C. Some tar separates from the gases in the upper portion of the tower and this may be distilled to pitch of high melting point by the incoming gases in the lower portion of the tower 60 or in the tower 61.

A hopper 63 is provided above the tower 60 to supply coal to the primary distillation chamber and this coal is preferably pulverized. The powdered coal falls in a shower thru the ascending hot gases, by which it is heated to effect drying and preliminary distillation. The top of the chamber 60 is enlarged, as shown at 64, to provide for reducing the velocity of the gases as they escape from the tower to allow coal particles carried by the gases to settle out of the gases back into the tower. The gases and vapors leaving the tower pass to a condenser 65 in which coke oven tar constituents are separated from the gases. This condenser may be the same condenser as that employed for cooling the balance of the coke oven gases from the battery 5b which are not collected in the hot gas header 10b. An exhauster 66 is provided for drawing the gases thru the system. A direct condenser is shown at 65 and separate means 67 and 68 are provided for separately drawing off ammonia liquor and tar from the decanter 69.

The coal preheated in the primary distillation chamber 60 is discharged into the secondary distillation chamber 61. Hot coke oven gases supplied from the hot gas header 10b thru the main 69' enter the bottom of this chamber and carbonize the preheated coal by direct contact as it falls thru the ascending hot gas stream. The coke produced is discharged to the sealed storage bin 70. The hot gases and vapors resulting from the coal carbonization process pass from the chamber 61 thru the main 71 to condensers 72. These condensers may be of any ordinary type. Direct condensers are shown. Fractional condensers may be employed where desired. An ex-

hauster 73 is shown for drawing the gases thru the system. The condensate comprises low temperature tar resulting from the carbonization of coal in the chamber 61 and coke oven tar present in the gases as they enter this chamber. The condensate produced in the condenser, together with any non-volatilized cooling liquid, is collected in the decanter 74. From this decanter the ammonia liquor and tar are drawn off into the decanters 75 and 76, respectively. Chamber 60 or 61 or both may be provided with internal agitating or scraping means.

Ordinary low temperature carbonization plants are expensive to install since they include a gas producer or other source of fuel gas and they are expensive to operate because of the heat required. However, when a low temperature retort is operated in combination with a coke oven battery or gas retort plant in which the waste heat of the fresh hot coal distillation gases is utilized for carbonizing the coal, as described and claimed herein, there is no necessity for a gas producer or other fuel gas plant for producing gases to be burned to provide the heat required in the low temperature carbonizing apparatus. The apparatus employed for the recovery of ammonia and light oils employed for treating the high temperature distillation gases may be used to treat the low temperature carbonization gases. The cost of installing a low temperature carbonization plant in combination with a coke oven plant or gas retort plant and the cost of operating such a plant in combination with a coke oven plant or gas plant may thus be materially less than the construction and operation of a low temperature carbonization plant at a point where foul hot coal distillation gases are not available. The type of low temperature carbonization apparatus employed may be selected with a view to preparing coke or semi-coke or gas required to meet any particular needs.

I claim:

1. The method of carbonizing coal and producing a blended high- and low-temperature-carbonization tar product at a coke oven plant, which comprises effecting high temperature carbonization of coal in coke ovens of the plant thereby producing coke and hot coal carbonization gases containing high-temperature-tar constituents, bringing the hot fresh coal carbonization gases into direct contact with coal so as to effect low temperature carbonization of the coal by the sensible heat contained in the coal carbonization gases and produce low-temperature-tar constituents therefrom, drawing off the resultant gases and vapors comprising high- and low-temperature-tar constituents and cooling them to recover a blended tar product comprising constituents resulting from the high temperature carbonization of coal and constituents resulting from the low temperature carbonization of coal.

2. The method of operating a coke oven plant for the production of a blended high-temperature-tar and low-temperature-tar product, which comprises effecting the high temperature carbonization of coal in coke ovens of the plant, collecting the resultant gases containing high-temperature-tar constituents from a portion of the ovens of the plant, bringing the hot fresh coal carbonization gases into direct contact with coal so as to effect the low-temperature carbonization of coal by the sensible heat contained in the coal distillation gases, drawing off the resultant gases and vapors comprising high- and low-tem-

perature-tar constituents and cooling them to recover a blended tar product comprising constituents resulting from the high temperature carbonization of coal and constituents resulting from the low temperature carbonization of coal, and regulating the temperature of the low temperature carbonization and the composition of the tar product by using for the low temperature carbonization gases from a selected stage of the high temperature carbonization cycle.

3. In combination with a coke oven battery, a primary distillation chamber and a secondary distillation chamber, means for feeding coal to the primary distillation chamber, means for bringing hot coke oven gases from the battery into direct contact with the coal in the primary distillation chamber to preheat the coal, means for discharging the preheated coal to the secondary distillation chamber, means for bringing the preheated coal into direct contact with hot coke oven gases from the battery in the secondary distillation chamber, and a condenser for cooling the gases and vapors leaving the secondary distillation chamber.
